UNITED STATES PATENT OFFICE.

FRANK H. HOUGHLAND, OF ST. LOUIS, MISSOURI.

FOLDING BOX.

SPECIFICATION forming part of Letters Patent No. 670,612, dated March 26, 1901.

Application filed December 22, 1900. Serial No. 40,802. (No model.)

To all whom it may concern:

Be it known that I, FRANK H. HOUGHLAND, a citizen of the United States, residing at St. Louis, in the State of Missouri, have invented 5 a certain new and useful Improvement in Folding Boxes, of which the following is a specification, reference being had to the accompanying drawings.

This invention is an improvement in boxes 10 which are capable of being shipped flat and yet be all ready to be placed in condition to hold the article or articles to be contained by them; and my desire is to provide a box of this character which while being very readily 15 collapsed will be locked in its box shape by the article it contains.

My object is attained by the box shown in the accompanying drawings, from which it will be seen that in addition to inventing a 20 box filling this requisition I have also produced one in which the inside of the box is perfectly plain, with no locks or places for the goods to catch, and thereby pull the box apart or collapse it.

25 My invention therefore consists in the peculiar constructions and arrangements of parts hereinafter described in detail and then definitely set forth by the claims at the end hereof.

30 In the accompanying drawings, which show several ways of carrying out my invention, Figure 1 is a perspective of the box in position for use with the parts broken away. Fig. 2 is a perspective view of the body of the 35 box partly collapsed, with the near side thrown outward instead of inward, with portions of the locking-strip broken away. Fig. 3 is a detail perspective view, on a smaller scale, of the box collapsed. Fig. 4 is a cross-section on line $x-x$ of Fig. 1. Fig. 5 is a perspective view of one end of the box partially folded, with the locking-strip thrown up and broken away. Fig. 6 is a plan view of the blank. Fig. 7 is a detail section showing a modified 45 form of securing the locking-strip to the end of the box. Fig. 8 is a perspective of another modified form in which the locking-strip is slipped into position instead of being cemented to the box. Fig. 9 is a section of 50 the same; and Fig. 10 is a perspective view

of a modification of the box thrown partly open, with the locking-strip extending from side to side instead of from end to end, as in the other figures.

Referring now to the details of said drawings by numerals, 1 represents the box shown in position for use in Fig. 1 and the main blank in flat form in Fig. 6. Referring at first to the blank, the large part in the center (marked 2) represents the bottom, the parts 60 marked 3 and 4 the ends, and those marked 5 and 6 the sides. Between each side and each end at each corner of the box are two parts, (marked 7 and 7^a), which are arranged to fold inwardly on the crease dividing them, 65 so as to double on each other, as shown in Figs. 4 and 6. Each of the ends has a pasting-flap 8 and each of the sides a reinforcing-flap 9, the use of all of which will be now described. 70

Permanently glued or otherwise secured to the pasting-flaps 8 and extending from one to the other is what I term a "locking-strip" 10, which is arranged with creases 10^a therein, so as to fold into the bottom of the box, 75 and thus form a supplemental bottom 10^b and supplemental ends 10^c and lock the box in position for use, as seen in Fig. 1. It will be evident that as this locking-strip is attached to the box at the top of its ends the more pressure that is placed on it the more tightly it will be pressed against the main bottom 2. After this box is in position for use and it is desired to collapse it the operator must place his fingers under the supplemental bottom 10^b and 80 "spring" it upwardly, when it can be made to assume the position shown in Fig. 2, and if pressure be exerted inwardly on the sides 5 and 6 these sides will be caused to fold flat against the main bottom 2, and the ends 3 and 90 4 will fold outwardly and downwardly until they and the bottom 2 are flat and in a straight line, when the locking-strip 10 will also be flat and cover the whole collapsed box from one end to the other, the sides folding inwardly under the locking-strip, as before described. 95

The foregoing is a description of my box in its simplest form; but to strengthen the box I fold the reinforcing-flaps 9 over on the sides 100

5 and 6, and may further strengthen these sides by inserting under said flaps 9 stiffening-strips 11. (Clearly shown in Figs. 1 and 4.) It will be observed that when the locking-strip is in position it completely covers the folding parts 7 and 7^a and the bottom edges of these strips 11 and that the upper edges of the latter are covered by flaps 9.

It will be evident that many modifications 10 and variations may be made and still retain the essence of my invention—*i. e.*, the locking-strip, which is “sprung” within the box and constitutes a supplemental bottom. For instance, a simple variation may be made by 15 leaving the pasting-flaps 8 off of the body of the box and forming their equivalents 8^a on the locking-strip, as shown in Fig. 7.

A further modification may be made, as shown in Figs. 8 and 9, wherein the locking-strip is made of the shape shown in perspective view, with the flaps 8^b simply slipped in the pocket between the ends and the folded parts. In this form the stiffening-strips 11 are dispensed with and one side of the locking-strip is formed with an integral stiffening-strip 11^a. On the other side of the box the side is extended and forms a cover 12. When this form of locking-strip is used, no pasting or other similar method of fastening is necessary, as actual practice has convinced me that if the flaps 8^b are inserted within the folds the desired purpose is effected. Therefore in the following claims where I use the term “attached” I mean the locking-strip to 35 be attached at its opposite edges by cementing, as in Fig. 1, or by being inserted in a pocket—for instance, as in the figures just described.

A further modification is shown in Fig. 10, 40 which is especially adapted for boxes which are deeper than they are wide, and in this case the locking-strip 13 is secured to the sides 14, and instead of the parts 15 of the blank between the sides 14 and ends 16 folding at the ends, as in Figs. 1 to 9, they fold 45 on the sides, as in Fig. 10.

All the reinforcing and stiffening pieces hereinbefore described may be omitted, if preferred; but for boxes intended to contain 50 heavy goods, such as shoes, I deem the use of them as decidedly advantageous.

It is obvious that further modifications and omissions may be made, so long as the essential features of my invention are retained.

55 The cover of my box is made in exactly the same way as the first form of box described herein—that is, like the box shown in Figs. 1 and 4, with the stiffening-strips left out; but as the cover looks exactly like the box, except as to its proportions, it is unnecessary to illustrate it. Therefore in the following claims when I refer to the term “box” I intend the claims to cover the box or its cover if made as defined by said claims.

65 What I claim as new is—

1. A folding box comprising a bottom, sides

and ends, and a single locking-strip having two of its edges attached to the box and arranged to be bent or creased intermediate of its attached edges and crowded down into and 70 lock the box in position for use, substantially as described.

2. A folding box comprising a bottom, sides and ends, the parts connecting the sides and ends folding inwardly on themselves, and a 75 locking-strip having two of its opposing edges attached to the box and arranged to be bent or creased intermediate of its attached edges and crowded down into and lock the box in position for use, substantially as described. 80

3. A folding box comprising a bottom, sides and ends, and a single locking-strip having its opposite ends attached to the ends of the box and arranged to be bent or creased intermediate of its attached edges and crowded 85 down into the box and against its bottom and thus lock the box in position for use, substantially as described.

4. In a folding box comprising a bottom, sides and ends, the parts connecting the sides 90 and ends folding inwardly on themselves, and a single locking-strip having its opposite ends attached to the ends and entering between said ends and said folded parts, the body of the locking-strip being arranged to be bent 95 or creased intermediate of its attached edges and crowded down into and against the bottom and thereby lock the box in position for use, substantially as described.

5. A folding box comprising a bottom, sides 100 and ends, the parts connecting the sides and ends folding inwardly on themselves and thus forming pockets in opposite ends of the box, and a locking-strip having its ends entering 105 these pockets and its body adapted to fold into the box against the bottom thereof and thereby lock the box in position for use, substantially as described.

6. A folding box comprising a bottom, sides 110 and ends, the parts connecting the sides and ends folding inwardly on themselves and thus forming pockets in opposite ends of the box, and a locking-strip having its ends entering 115 these pockets and its body adapted to fold into the box against the bottom thereof and thereby lock the box in position for use, the said locking-strip being provided with an integral reinforcing-strip, substantially as described.

7. A folding box comprising a bottom, sides 120 and ends, one of the sides having a cover formed integral therewith, and a single locking-strip having its opposite ends attached to the ends of the box and arranged to be bent 125 or creased intermediate of its attached edges and crowded down into the box and against its bottom and thus lock the box in position for use, substantially as described.

8. A folding box comprising a bottom, sides 130 and ends, the parts connecting the sides and ends folding inwardly on themselves and thus forming pockets in opposite ends of the box,

one of the sides being formed with an integral cover, and a locking-strip having its ends entering these pockets and its body adapted to fold into the box against the bottom thereof and thereby lock the box in position for use, substantially as described.

5 In testimony whereof I affix my signature,

in the presence of two witnesses, this 20th day of December, 1900.

FRANK H. HOUGHLAND.
